CLEANING HEAD FOR MOPS

Amos H. Marchus, Oakland, Calif.

Application May 15, 1948, Serial No. 27,340

1 Claim. (Cl. 15—147)

1. **1**

The invention, in general, relates to surface cleaning equipment and more particularly relates to an improved mop head for affording the effective mopping of floors in a more expeditious manner and affording long life for the device.

It is perhaps well known that the majority of mops and mop heads heretofore marketed for dry mopping or partially dry and partially waxing a floor surface generally comprise a mass of individual strands of coarse fibre, string or yarn all fastened together to a frame which is removably fastened to an operating handle. Some of these prior mopping devices consist of a pulpy mass of suitable, yieldable material encased in cloth or fibre. The former types of mops are disadvantageous because of the continual loss of individual strands of yarn, string or the like and the consequent reduction in size of the mop head as well as ultimate loss of value entirely. Moreover, these former types of mops become matted or cemented together by virtue of the accumulation of wax or other cleaning substance thereon. In both types, these disadvantages are reflected in poor mopping operations and these prior mops or mop heads have relatively short lives.

A primary object of the present invention is to provide an improved mop head which is highly effective in cleaning floor surfaces in a minimum of time, including the corners of the room, and which is extremely durable and has an increased period of use.

Another important object of my invention is to provide an improved mop head of the indicated nature which is additionally characterized by its lightness in weight permitting even slight women to handle the same readily.

A still further object is to provide an improved mop head of the aforementioned character which presents a firm but yielding mopping surface, and which cannot become soiled or lose any of its parts, or which otherwise deteriorates.

The foregoing and other objects are attained in a preferred embodiment of my invention which is illustrated in the accompanying drawings. It is to be understood that I am not to be limited to the precise embodiment shown, nor to the precise arrangement of the various parts thereof, as my invention, as defined in the appended claim, can be embodied in a plurality and variety of forms.

Referring to the drawings:

Figure 1 is a plan view of a preferred embodiment of the invention showing the mop head attached to an operating handle, the latter being broken away to indicate length.

2. **2** Figure 2 is a sectional view taken on the line 2—2 of Figure 1.

Figure 3 is an end view of the preferred embodiment of the invention, looking from the handle end thereof.

Figure 4 is a side elevational view of the preferred embodiment of the invention, the operating handle for the same being shown in fragmentary view.

10. In its preferred form, the improved mop head of my invention preferably comprises a molded body of relatively stiff but resilient material, such as rubber; said body being of generally triangular shape and having a handle socket formed therein adjacent to its wide end and being thickened at its wide end but tapering in thickness to a relatively thin cross-section at the apex of the triangle of the body, and means on said body for detachably fastening a cover thereon.

As particularly illustrated in Figures 1 and 2 of the annexed drawings, my improved mop head is formed to a triangular shape and preferably from molded rubber, although any other material having the characteristics of relative stiffness and yieldability or resiliency may be used.

15. The molded rubber body of the mop head, which conveniently is designated by the reference numeral 11 in the annexed drawings, also is provided with a pair of nibs 12 and 13 on its base 14 at opposite sides of the center thereof, such nibs being adapted to receive tie strings or the like of a cloth or fabric covering, not shown, for the mop head. In forming the mop head 11, the edges of its sides 16 and 17 are formed straight 20. Similarly, the junctures 19 and 20 between the base 14 and the two sides 16 and 17 are rounded thus eliminating all likelihood of fraying the rubber at these three points.

25. In accordance with my invention, the molded rubber body 11 is formed to an appreciable thickness adjacent to the base 14 and of relatively thin cross-section adjacent to the apex 18, the taper between the base 14 and the apex 18 being gradual and uniform on both the top and the bottom of the body, all as clearly illustrated in Figures 2 and 4 of the accompanying drawings. Moreover, the body 11 is formed transversely with a reinforced section approximately 30. at the center of the body; such reinforced section being indicated in dotted lines in Figure 2 and bearing the reference numeral 21 in Figures 1 and 2 of the drawings. In view of the triangular shape of the body 11 as well as the tapering thickness thereof, the reinforced section 21 is of

generally triangular shape also and is somewhat thicker adjacent to the base 14 than at the apex 18 of the body.

In order to afford the attachment, in locking or latching relationship, of a suitable handle for the mop head, I provide a special type of handle socket 22 within an extension 22a of the mop head at the base end thereof. The handle socket 22 preferably is so formed as to define interior shoulders 23 and 24 and is tapered so as to snugly receive and interlock with a tapered or oval shaped ball or bead 26 formed on the inner end 27 of an operating handle 38. The effect the latching of the handle in operative position, the handle 28 is reduced adjacent to the ball or bead 26 thus defining a groove for fitting the rim 29 of the handle socket 22. This construction is shown clearly in Figures 2 and 3 of the annexed drawings. It is to be particularly observed that the reinforcing section of the body 11 is carried or extended over the material defining the handle socket 22 thus strengthening the mop head at this point.

Due to the ready resiliency of the mop head body 11, the same can be flexed and bent to substantially a right angle in use for mopping a floor surface with either the top of the body or the bottom thereof in engagement with the surface. Notwithstanding the fact that in use the body 11 is so flexed as to be nearly at right angles to the handle 28, the body 11 will spring back into alignment with the axis of the handle whenever it is lifted from the surface against which it is pressed when mopping a surface. In other words, the improved mop head of the present invention can be used a multiplicity of instances without permanent distortion of the body 11 because of its high resiliency. By virtue of the provision of the reinforcement ridge or section at its center, there is no likelihood that the body 11 will become fissured or otherwise break despite repeated use. The straight edges of the sides 16 and 17 of the body merging into an apex afford effective cleaning of room corners since the straight edges of the sides permit fitting the mop head closely to the adjacent room walls at the corners. The mop head conveniently and readily can be removed from a mop handle whenever it is desired to replace a soiled covering, by merely twisting or bending the body 11 at the

5 juncture of the mop head and handle to release the locking effect caused by the engagement of the interior shoulders of the handle socket with the reduced portion of the handle, thus permitting the handle to be withdrawn from the socket.

It is to be understood that the appended claim is to be accorded a range of equivalents commensurate in scope with the advance made over the prior art.

10 I claim:

15 A cleaning head for a mop consisting of a generally triangular resilient body comprising a base, an extension projecting from the transverse center of said base; said extension having a socket therein for the reception of a handle for the head, a pair of sides merging with said base, an apex at the juncture of said sides; said apex being rounded and the junctures between said base and said sides being rounded; said body having a relatively thick section at said base and uniformly tapering to a relatively thin section adjacent to said apex, and a reinforcing section adjacent to the transverse center of said body and extending from the obverse as well as reverse of said body; said reinforcing section 20 likewise being relatively thick in cross-section adjacent to said base and uniformly tapering to a relatively thin section adjacent to said apex.
